UNITED STATES PATENT OFFICE.

OSCAR JOHANSEN, OF CHRISTIANIA, NORWAY.

WASTE-MAKING MACHINE.

1,363,420.

Specification of Letters Patent. Patented Dec. 28, 1920.

Application filed July 31, 1919. Serial No. 314,531.

To all whom it may concern:

Be it known that I, OSCAR JOHANSEN, a citizen of the Norwegian Monarchy, and resident of Christiania, Norway, have invented certain new and useful Improvements in Waste-Making Machines, of which the following is a specification.

This invention relates to machines for making waste from cotton, cloth, rags or other similar material as clothing, curtain material or the like.

The object of the invention is to provide a machine of the character set forth of simple, novel and practical construction and design.

One object of the invention is to provide novel means for picking out the weft of the material after it has been cleaned so as to produce long clean waste.

Another object of the invention is to make the several parts of the machine easily accessible. Still another object of the invention is to provide means for automatically stopping the machine in the event it becomes clogged by the bunching or too heavy feeding of the material.

With the above and other objects in view the invention is embodied in a waste making machine as hereinafter described and as illustrated in the accompanying drawings, in which—

Figure 1 is a side view of the machine with parts in section;

Fig. 2 is a plan view of the machine with parts in section and parts broken away;

Fig. 3 is a front view of the machine;

Fig. 4 is a rear view of the machine;

Fig. 5 is an enlarged sectional detail view of the picking elements and associated parts;

Fig. 6 is a plan view development of the picker plate which operates with the picking elements;

Fig. 7 is a sectional view of the picker plate;

Fig. 8 is a detail view of parts of the gearing.

The reference numerals 1 and 2 denote the two side frames of the machine and which form the principal supporting elements thereof. The numeral 3 denotes a large picking drum provided with steel pins 4 of which there are about 6000 placed in staggered relationship as will be understood.

Forward of the said drum 1 is located a small picking drum 5 provided with about

300 steel pins 50 in staggered relationship to the pins 4 on the large drum. Forwardly of the small picking drum 5 are located the two knurled feeding drums 6 and 7. A 60 guard 8 with a door 9 covers the large drum 1. 10 is a conveying belt driven over two preferably wooden rollers 11 and 12 and above a supporting board or table 13. 14 is a small roller for bridging between the conveying belt 10 and the feed drums 5, 6.

On each side of the machine there is suitably pivoted at 15 a hook 16. The hooks 16 overlap and keep in place a transverse flat bar 17. Springs 18 on bolts 19 which pass through said bar keep the latter up against the hooks 16.

The bolts 19 are carried by arms 20 against which the lower ends of the said springs 18 act. The arms 20 carry a sleeved 75 rod 21. To the latter there are pivoted two presser arms 22, 22 which are kept down upon the upper feed drum 6 by springs 23, 23, acting on said presser arms. Thus, the feed drums are kept together by spring pressure, the lower one being carried by the side frames as will be understood.

To the side frames are secured a transverse bar 24 and in the latter is fastened a picker plate 25, see Fig. 6. The picker plate 85 is bent up over the small picker drum and down between and under the large picker drum. The picker plate is provided with slots 26 through which the pins 50 on the small drum project, while opposite the pins 4 on the large drum, the picker plate is provided with grooves 27. Above the small drum and secured to the arms 20 aforesaid is a picker shield 28 with grooves 29 for the pins 50.

The driving elements are as follows: The shaft 29 of the big picker drum 3 is provided with the usual fast and loose pulleys 30 and 31. 32 is the belt which is shifted by the belt shifter 33 slidably carried by a shaft 100 34. The belt shifter is operated by a forked arm 35 on a shaft 36 which carries a bevel gear 37 in mesh with a toothed sector 38 on the starting shaft 39 which is provided with an off set or crank 40 adapted to lift the 105 brake lever 41 which carries a weight 42. The brake lever is pivoted at 43 and carries a brake shoe 44 adapted to coöperate with the brake disk 45 fast on the large drum shaft 29.

The starting shaft 39 extends across the machine and carries a handle 47. 48 is a

guide plate for the handle 47. While the machine is running the handle stands in a notched cut out 52 in said guide plate in the position shown in Figs. 1 and 2. When it is desired to stop the machine the handle 47 is thrown to the left in these figures and the starting shaft 39 is thus rotated. This in turn shifts the belt from the fast to the loose pulley 31 through the instrumentality of the members 38, 37, 36, 35 and 33. At the same time, however, the crank 40 is also lowered away from the brake lever, which is thereupon operated by the weight 42 to brake the machine. The reverse movement of the handle 47 throws off the brake and puts the belt on the fast pulley.

The small picker drum 5 is driven from the shaft 29 through a reduction train of gearing generally indicated by the numeral 58 in which the gear 54 which is loose on the driven shaft 57 drives a tooth 55 carried by a collar 56 slidably mounted on the shaft 57 of the small drum, 5. The collar 56 is mounted on the shaft 57 by a key as shown and the tooth 55 on said collar is held in driving engagement with the gear 54 by a spring 59, Fig. 2. The collar 56 operates a clutch lever 57 pivoted at 58 and adapted to knock the handle 47 out of the notch 52.

The operation is as follows: The material is fed into the machine by the conveying belt 10 and passes in between the feed rollers 6 and 7 and is caught by the pins 50 in the small picker drum and carried around on said drum and under the picker shield 28 which serves to keep the material on said pins 50 under pressure from the springs 18. The pins 50 in the small drum act as holding or retarding means on the material which is picked and made into waste by the pins 4 on the large drum. The pins 4 grip the material one thread at a time and pull out the weft threads from the warp threads, while the pins 50 retard said pulling action and hold on to the material. The small drum is cleaned by means of pickers 60 mounted below the same. In the event the material should crowd or bunch, the rotation of the small picker drum will be retarded, this in turn will cause the collar 56 to have a tendency to move slower than the gear 54 and consequently the tooth 55 will be forced out of driving connection with said gear and against the action of the spring 59, the clutch lever will be operated and the handle 47 will be thrown in to stopping position and the machine will automatically stop.

When it is desired to clean the machine or for other reasons, the hooks 16 are swung away from the bar 17 which then is forced up by the springs 18. This relieves the pressure in the arms 20, rod 21 and arm 22, also on the shield 28, after which the latter may be lifted off and access had to the small picker drum. Fig. 8 shows a train of gear-

ing 70 for driving the shaft 71 on the feed drum 7 and the shaft 72 of the roller 11 from the shaft 57 of the small drum 5.

While the invention has been illustrated in what is considered its best application, it may have other embodiments without departing from its spirit and is not, therefore, limited to the structures shown in the drawings.

I claim;—

1. In a waste making machine, a drum for receiving the material to be acted upon, a picking drum, rigid means for guiding the material around the said first named drum and to and around a portion of the said second named drum, said rigid means being arranged to partially encircle said second drum, and yieldingly mounted pressure means adapted to keep the material in contact with and upon the said first named drum.

2. In a waste making machine, a drum, means thereon for receiving and gripping the material to be acted upon, a second picking drum for receiving the material from the said first drum and tearing said material, means for guiding the material, said guiding means comprising a fixed guide plate bent up over the said first drum, down between the said two drums and partially bent around the said picking drum, pressure means for keeping the material on said first named drum and means for yieldingly pivoting said pressure means above the said guide plate.

3. In a waste making machine, a drum, pins on said drum, a second drum, pins on said second drum, a plate for guiding the material from the first drum to the second drum, said plate having slits through which the said pins on the said first named drums are adapted to project, said plate being further provided with grooves spaced in staggered relationship with the said slits, into which grooves the pins on the said second drums are adapted to project.

4. In a waste making machine, a pair of drums for receiving and picking the material to waste, pins on said drums, a plate partially encircling both of said drums for guiding the material around the same, yielding pressure means for keeping the material on one of said drums and for co-operating with the said plate to guide said material onto the other of the said drums and pivoted supporting means for said pressure means whereby the latter is adapted to be moved away from the said drums.

5. In a waste making machine, a rigidly mounted plate for guiding the material and having a plurality of parallel slots, yieldingly mounted pressure means disposed in spaced relationship with respect to the slotted portion of said plate, a drum, pins on said drums projecting through said slots and

adapted to receive the material and carry it between the said plate and the said pressure means away from the latter, a second drum, pins thereon and means for operating said 5 second drum to receive the material from the said first named drum.

6. In a waste making machine, a rigidly mounted plate for guiding the material and having a plurality of parallel slots, yieldingly mounted pressure means disposed in 10 spaced relationship with respect to the slotted portion of said plate, a drum, pins on said drums projecting through said slots

and adapted to receive the material and carry it between the said plate and the said 15 pressure means away from the latter, a second drum, pins thereon and means for operating said second drum to receive the material from the said first named drum and means for automatically stopping the operation of said machine when the quantity 20 of material moved between said plate and the pressure means is greater than a predetermined quantity.

Signed at Christiania, Norway.
OSCAR JOHANSEN.
